(57) **CLAIM**

The ornamental design for a dynamic compression device, as shown and described.

DESCRIPTION

FIG. 1 is a perspective view of a dynamic compression device, according to the present disclosure;

FIG. 2 is a second perspective view, thereof;

FIG. 3 is a third perspective view, thereof;

FIG. 4 is a fourth perspective view, thereof;

FIG. 5 is a fifth perspective view, thereof;

FIG. 6 is a front view, thereof;

FIG. 7 is a back view, thereof;

FIG. 8 is a side view, thereof; and,

FIG. 9 is another side view, thereof.

The broken lines illustrate portions of the dynamic compression device that form no part of the claimed design.

1 Claim, 9 Drawing Sheets
